United States Patent Office.

JAMES NOBLE, OF PITTSBURG, PENNSYLVANIA.

Letters Patent No. 76,938, dated April 21, 1868.

IMPROVED LOCOMOTIVE COW-CATCHER.

The Schedule referred to in these Letters Patent and making part of the same.

TO ALL WHOM IT MAY CONCERN:

Be it known that I, JAMES NOBLE, of the city of Pittsburg, in the county of Allegheny, and State of Pennsylvania, have invented a new and useful Improvement in Cow-Catchers; and I do hereby declare the following to be a full, clear, and exact description thereof, reference being had to the accompanying drawing, making a part of this specification, and to the letters of reference marked thereon—

Figure 1 being a front elevation of a railroad-locomotive with my improved cow-catcher attached, and

Figure 2 being a vertical section passing through the cow-catcher and the axle of the forward pair of truck-wheels along the line $x x$, fig. 1.

My improved locomotive cow-catcher consists of a cylinder, or a number of cylinders, connected by gearing to the axle of the forward pair of truck-wheels in such way that as the locomotive moves forward, such cylinder or cylinders will revolve in a direction opposite to the direction of the rotary motion of the car-wheels, such cylinder or cylinders having properly-shaped projections on their periphery for catching and raising clear of the track any object with which they may come in contact. The cow-catchers in ordinary use have been found insufficient to remove from the track any animal of considerable size. Such animals get under the cow-catcher and force the locomotive off the track, with consequent destruction of property, and in many cases loss of life.

To enable others skilled in the art to make and use my invention, I will proceed to describe its construction and mode of operation.

$a a$ represent the rails of the railroad-track. $b b$ are the forward wheels of the forward truck, connected together by the axle e . d is a part of the truck-frame by which support is given to the boiler f , smoke-stack g , &c., as in the ordinarily constructed locomotive. The truck-frame d extends forward a sufficient distance to furnish bearings for a cylinder or series of cylinders, g , the axis of which is parallel with the axle e . Such cylinders, g , are, by gear-wheels $m m'$, so connected to the axle e as to receive a rotary motion therefrom. The peripheries of the cylinders g are serrated or have projecting pins or teeth, i , of such number, arrangement, size, and shape as to catch any object which may come in their way and raise it clear of the track.

An apron, n , extends from the end of the boiler f forward over the truck, and it is slotted at suitable intervals, so that the projecting parts n' shall come between the small cylinders g , or, if a single cylinder be used, they shall occupy a portion or all the space between the rows of teeth, i . If desirable, grooves may be cut in the face of the single cylinder g , in which grooves the projecting parts n' of the apron may rest. The cylinder g may operate near to the track, or considerably above it, as may be preferred.

The operation of the devices thus described is as follows: The locomotive, in moving forward, causes the front part of the cylinder or cylinders g to revolve upward. If the cow-catcher comes in contact with an object on the track, it catches it, raises it up, and prevents it from passing under and throwing the locomotive off the track. If the object is raised up to the height of the top of the cylinder, as will frequently be the case, such object is deposited on the apron n , and prevented from otherwise interfering with the free and safe progress of the locomotive.

Instead of a single cylinder, or a number of cylinders, a series of toothed wheels may be used with like effect and mode of operation, or two cylinders may be adjusted at an obtuse angle to each other, the apex of the angle being forward, and connected by bevel-gearing to the axle e . Their motions and mode of operation will be the same as is above described, except that they will tend to throw any body, against which they may impinge, off, as well as raise it clear of the track.

By the use of the devices above set forth, it will be exceedingly difficult, not to say impossible, for any object to get under the cow-catcher or forward truck-wheels, of sufficient size to throw the locomotive from the track.

Hence, what I claim as my invention, and desire to secure by Letters Patent, is—

1. The construction of a locomotive cow-catcher, consisting of a revolving cylinder or cylinders with face or

faces serrated or toothed, and so connected with the forward locomotive-truck as to receive the motions described, and operate substantially as and for the purposes hereinbefore set forth.

2. An apron, *n*, extending from some fixed part of the locomotive forward over a revolving cylindrical cow-catcher, *g*, substantially as and for the purposes hereinbefore set forth.

In testimony whereof, I, the said JAMES NOBLE, have hereunto set my hand.

JAMES NOBLE.
